UNITED STATES PATENT OFFICE.

THOMAS LANGSTON, OF MERIDEN, CONNECTICUT, ASSIGNOR TO EDW. MILLER & CO., OF SAME PLACE.

LANTERN.

SPECIFICATION forming part of Letters Patent No. 279,403, dated June 12, 1883.

Application filed March 16, 1883. (No model.)

To all whom it may concern:

Be it known that I, THOMAS LANGSTON, of Meriden, in the county of New Haven and State of Connecticut, have invented a new Improvement in Lanterns; and I do hereby declare the following, when taken in connection with accompanying drawings and the letters of reference marked thereon, to be a full, clear, and exact description of the same, and which said drawings constitute part of this specification, and represent, in—

Figure 1, a sectional side view; Fig. 2, a section through the ring H, showing the stud in the locking-slot; Fig. 3, a modification; Fig. 15 4, a modification of the lower globe-holder.

This invention relates to an improvement in lanterns such as are provided with a fount for oil, made as a permanent base to the lantern, a concentric burner, a globe resting upon the base around the burner, and with a ring resting upon the top of the globe, through which the products of combustion escape, commonly called "hand-lanterns;" and while the invention is particularly adapted to that class of these lanterns in which the air to support combustion, or a portion of it, is received through vertical tubes opening from above and leading the air downward into the base around the burner, whence it passes up through the burner, it is applicable to other classes of lanterns, the object of the invention being to construct the globe-holding devices, so that the globe and its supporting devices may be readily raised for the purpose of trimming or lighting, and yet permit the easy removal of the globe from the lantern when occasion requires; and the invention consists in a globe combined with a support for its base and a support for its neck, each independent of the other, and springs arranged to force the base and neck holding devices upward to clasp the globe between said base and neck holding devices, the said neck-holding device provided with a locking mechanism which will secure the globe and the holding devices in their down or closed position, said springs permitting the separation of the base and neck holding devices, whereby the globe may be removed, as more fully hereinafter described.

50 A represents the base of the lantern, B the burner, C C the tubes which conduct air into

the base, D the flange around the top, which supports the upper end of the tubes, all of a construction too well known to require detailed description.

55

E is a plate which surrounds the cone of the burner, preferably perforated, and upon which plate the lower end of the globe F rests.

G G are two vertical tubes, one arranged at each side, and secured in position, may be, to the tubes C C or to the flange D. Within these tubes a helical spring, a, is arranged, resting on an internal flange, b, at the bottom of the tubes, and through each of these springs a rod, d, extends upward, provided at its upper end with a disk or head, e, which rests upon the upper end of the spring. These rods are connected to the plate E by an arm, f, or otherwise. The tendency of these springs is to force the plate E upward. Therefore when 70 the plate E is in its lowest position around the cone the springs are compressed within the tubes, as shown in Fig. 1, so that the reaction of the springs will be to raise the plate E. At the upper end the usual ring, H, is arranged 75 through the flange D, but so as to be moved and guided freely up and down through said flange, and is provided with the usual wind-guard, I, at the top. This ring H fits the neck of the globe, and is provided with an inverted-L-shaped slot, h, into which a stud, i, on the flange D extends. The vertical part of the slot permits the ring to be moved up and down; but when down and turned to take the stud i into the horizontal part of the slot the 80 ascent of the ring is prevented. When the ring H is in its down position and locked by having been turned to bring the stud i into the horizontal part of the slot, the globe and its plate E will have been forced down to their 85 lowest position and the springs compressed. Then when the ring H is turned to bring the stud i into the vertical part of the slot the springs draw up the base and globe and throw up the ring until the lower end of the vertical 90 part of the slot strikes the stud, and as seen in broken lines, Fig. 1. The springs pull upward upon the globe and retain the globe between its holding devices in this up position, and so far above the burner that the wick may 95 be trimmed or lighted or the flame extinguished, as the case may be. Then to return

100

the globe, simply press the ring H downward until the horizontal part of the slot h again engages the stud i. If at any time it is desirable to remove the globe, it is only necessary to take hold of it with one hand and hold it in its down position, while with the other the ring H is raised from the neck of the globe so as to free the globe from its connection with said ring. To replace the globe, set the lower end upon the plate E while the ring is raised; press it downward until the neck of the globe will pass under the ring; then the spring will draw the globe up into contact with the ring.

15 While I prefer to arrange the tubes for the springs above, and so as to draw up the globe, they may be below, as seen in Fig. 3. In this case they have substantially the same action upon the plate E or holder for the lower end 20 of the globe.

While I prefer the inverted-L-shaped slot h, with the stud, as a means for locking the upper holding-ring in its down position, it will be readily seen that other locking or latching mechanism may be employed, it only being essential that the securing mechanism for the neck of the globe shall be free for vertical movement, and locked to hold the globe in its down position, and yet independent of the 25 lower holding devices, so that the said holding devices may be separated for the removal of the globe, as hereinbefore described.

While I have illustrated the ring H as arranged through the flange D as a guide for its vertical movement, in other classes of lanterns a different arrangement for such guiding may be made, it only being essential that the holding devices for the upper end of the globe shall be free for vertical movement, either under 30 the action of the springs or independent thereof, as hereinbefore described.

Instead of connecting the rods with the springs so as to compress the springs by the downward movement of the lower holder, the 35 springs may be secured at the upper end and the rods attached to the lower end, so that the downward movement of the lower holder will extend the springs, and then the contraction of the springs will raise the holder.

In some cases the plate E is not employed, 50 the globe standing directly on the base. In such case the support for the lower end of the globe, and to which the springs are attached, will be a ring around the lower end of the globe, as seen in Fig. 4. In some cases the 55 plate E may be made fast to the base, and the same ring as shown in Fig. 4 employed as the support or holder for the lower end of the globe.

I claim—

1. In a lantern substantially such as described, the combination of a holder for the lower end of the globe, springs in connection with said lower holder, the action of which is to raise said holder, a globe supported on said 65 lower holder, and a holder for the upper end of the globe, arranged for vertical movement and independent of the lower holder, with a locking device to secure said upper holder in its down position, substantially as described. 70

2. In a lantern substantially such as described, the combination of a holder for the lower end of the globe, a holder for the upper end of the globe, a spring or springs in connection with the holder for the lower end of 75 the globe, the action of which is to raise the said lower holder, globe, and upper holder, and a locking device to secure said holders and globe in the down position, substantially as described. 80

3. The combination of the lower globe-holder, vertical tubes G, helical springs a, arranged therein, with rods d, connecting said springs with said lower globe-holder, the ring H, supported in suitable guides above and arranged to embrace the neck of the globe, and with a locking mechanism to secure said ring, globe, and lower holder in their down position, substantially as described. 85

4. In a lantern, the combination of a globe 90 arranged to slide up and down with a spring arranged to lift the globe and hold it in its raised position and a fastening to hold it in its depressed position, substantially as described.

THOMAS LANGSTON.
